UNITED STATES PATENT OFFICE

2,520,135

WARPING APPARATUS

Russell P. Drake, Caledonia, Ill., assignor to Barber-Colman Company, Rockford, Ill., a corporation of Illinois

Application March 29, 1946, Serial No. 658,247

9 Claims. (Cl. 28—51)

1

The invention relates to warping apparatus of the type in which yarn from a substantial number of yarn masses are wound onto a single relatively large container; and the invention has particular reference to warpers for winding rayon and other filament yarn upon a warp beam driven at high speed by frictional contact between the warp on the beam and a driving drum.

In warping rayon and the like, it is necessary in order to avoid injury to the filament to minimize the pressure between the beam and the drum. It has been found, however, that when the driving pressure is reduced sufficiently to avoid injury to the filament, it is insufficient to bring the warp beam to a stop quickly when the driving drum is brought to rest through the operation of the usual brake mechanism. Accordingly, the warp beam continues to rotate after stoppage of the drum with a resulting skidding or sliding of the delicate filament upon the surface of the drum. This has been found highly objectionable because of the injury to the filament threads, weakening them for subsequent operations or fraying the same so as to produce ends which show up in the weaving.

The primary object of the present invention is to provide warping apparatus including a warper having brake mechanism operative to stop simultaneously both the driving drum and the warp beam.

A further object is to provide a brake mechanism for the warp beam utilizing the beam heads as the braking surfaces and so constructed and arranged as not to interfere with the placement of the beam upon its supporting means and its removal therefrom.

Another object is to provide a beam brake mechanism comprising brake shoes supported for movement toward and from the beam heads and also capable of pivotal movement with the beam as the latter moves upwardly during the winding operation.

A further object is to provide a brake mechanism of the character last above indicated in which the pivotal brake shoes are maintained in uniformly spaced relation to their respective heads during the normal operation.

The objects of the invention thus generally set forth, together with other and ancillary advantages, are attained by the construction and arrangement shown by way of illustration in the accompanying drawings, in which:

Figure 1 is a fragmentary side elevational view of a warping apparatus including a warper, creel and control mechanism therefor, the warper be-

ing equipped with brake mechanism constructed in accordance with my invention.

Fig. 2 is a fragmentary horizontal sectional view taken approximately in the plane of line 2—2 of Fig. 1.

Fig. 3 is an enlarged vertical sectional view taken approximately in the plane of line 3—3 of Fig. 2 and showing the beam brake mechanism with the brakes applied.

10 Fig. 4 is a fragmentary detail view on an enlarged scale of a part shown in Fig. 4, but showing the brakes off.

Fig. 5 is a fragmentary plan view of the same with a supporting bracket shown in section.

15 Referring first to Fig. 1 of the drawings, I have shown my invention as applied to warping apparatus comprising a warper 1, having means for rotatably supporting a warp beam 2 upon which a multiplicity of filament threads 3 are to be wound simultaneously. The filament threads being wound are supplied from a creel 4 supporting a multiplicity of packages or cheeses 5, two only herein being shown. Operatively associated with each of the cheeses supported on the 20 creel is a drop wire 6 responsive to the breakage of a filament thread and operative to control a reset mechanism 7 so as to interrupt the operation of the warper.

25 As in conventional practice, the warp beam is rotatably supported upon a pair of pivoted arms 8, the yarn being wound upon a central cylindrical core 9 between circular end plates or heads 10. Operatively associated with the supporting arms 8 is a let off mechanism generally 30 designated 11 for controlling the driving pressure between the yarn mass on the warp beam and a driving drum 12. The let off mechanism 11, which is of conventional construction, is capable of adjustment to vary the degree of driving pressure between the beam and the drum.

35 The drive mechanism for the warper is of the general character disclosed in Peterson Patent No. 1,672,470, dated June 5, 1928. In brief, it comprises a main drive shaft 13 driven from an electric motor 14 through the medium of a clutch 15, the shaft 13 having a driving connection with the drum comprising a spur gear train generally 40 designated 16. The clutch 15 is arranged for engagement and disengagement by the operation of a rockshaft 17 under the control of the reset mechanism 7, and coincidentally with the disengagement of the clutch 15 a brake 18 is engaged to stop the drum.

45 The control shaft 17 tends to rock in a clockwise direction (Fig. 1) under the action of a

2

contractile spring 25 but is normally restrained from such rocking movement by a detent means forming part of the reset mechanism 13. The shaft 23 has rigid therewith an arm 26 connected by a link 27 with one arm of a bell crank 28 of the reset mechanism. Another arm of the bell crank is normally supported by a detent 29 arranged for actuation by a solenoid 30 when the latter is deenergized under the control of any one of the drop wires in response to the breakage of a filament thread. When the solenoid is energized, the bell crank and its connected rockshaft 23 are released for operation by the force of the spring 25. In the ensuing rocking movement of the shaft 23, the clutch 21 is disengaged and the brake 24 engaged in the general manner set forth in said Peterson Patent No. 1,672,470. It will be understood that the reset mechanism per se forms no part of the present invention. For a more complete disclosure thereof, attention is directed to Peterson et al. Patent No. 2,172,850, dated September 12, 1939.

The present invention contemplates the provision of a brake mechanism for stopping the warp beam coincidentally with the stoppage of the driving drum. To this end I have provided an auxiliary brake mechanism together with means for controlling the same concurrently with the control of the drum brake mechanism. This beam brake mechanism is especially constructed so as not to interfere with the removal or replacement of the warp beam, and at the same time it is adapted for uniform operation notwithstanding the fact that the warp beam moves gradually upward in the growth of the yarn mass on the beam.

Referring now to Figs. 2 and 3, the beam brake is supported by the machine frame and in the preferred embodiment comprises a pair of brake shoes 31 respectively associated with the opposite beam heads 16. The brake shoes are carried by two slides 33 mounted for movement toward and from the warp beam, and are so supported as to be capable of swinging to compensate for the changing positions of the beam as the winding proceeds. As shown, the shoes are pivoted to extensions 32 of the slides.

Each slide 33 is composed in the present instance of a pair of bars 34 (Fig. 3) connected by bolts 35 with spacers 36 and 37 therebetween. In the present instance, the slides are mounted for sliding movement upon a pair of transverse parallel rods 38 and 39 fixedly supported in the warper frame, the former serving to support the beam arms 14. Secured to these rods on opposite sides of the slides are suitable guide members 40 (Fig. 2) engaging with the opposite sides of the slides to guide the latter in their movement toward and from the brake beam.

The slides 33 are urged toward the brake beam so as to carry the brake shoes 31 into engagement with the beam heads 16, by spring means comprising in the present instance a plurality of coiled tension springs 41 (Fig. 3) suitably anchored to an adjustable stationary plate 42 and connected to a depending arm 43 at the rear end of the slide. Movement of the slides toward the beam is normally restrained by the detent means of the reset mechanism 13. For this purpose, the control shaft 23 is operatively connected with a parallel rockshaft 44 having arms 45 at opposite ends connected with respective slides 33. The rockshaft 44 is connected with the shaft 23 through the medium of a pair of arms 46 and 47 (Figs. 1 and 2) respectively rigid with the shafts

5 44 and 23 and connected by a link 48; and the connection between the arms 45 and the respective slides is accomplished by means of pins 49 on the free ends of the arms 45 and arranged to move into engagement with the ends of the slides remote from the beam (Fig. 3) when the slides are released.

When the reset mechanism 13 is operated to stop the warping apparatus, as for example when a filament thread being wound breaks so as to release its drop wire, the solenoid 30 is deenergized so as to withdraw detent 29 from supporting relation to the bell crank 28, thereby releasing the control shaft 23 to the action of spring 25. In addition to effecting disengagement of the clutch and application of the brake for the winding drum as above set forth, such rotation of shaft 23 is transmitted to rockshaft 44 and its arms 45 so as to release the slides 33 to the action of their respective spring means 41. It will be observed that the pins 49 are received relatively loosely within the rear ends of the slides 33 so as to permit application of the brake shoes notwithstanding considerable variations in the size of the beam heads 16.

25 The brake shoes 31 are preferably supported clear of the peripheral surfaces of the beam heads 16 during the normal winding operation, thereby avoiding undue wear upon the coacting brake surfaces and preventing bouncing movement of the brake shoes toward and from the drum. For this purpose, I provide a support for each brake shoe comprising, in the present instance, a stop pin 50 supported by the beam arm 14 and engageable with the shoe during the normal winding operation so as to hold the shoe clear of the beam head. In this connection, it will be seen that the center of gravity of the shoe is such as to cause the upper end of the shoe to tilt forwardly, and the lower end rearwardly against the stop pin 50.

40 The stop 50 is supported from the beam arm by means of a depending bracket 51, and in the preferred construction the stop is so supported as to be capable of yielding. Thus it is carried by a bifurcated member 52 straddling the bracket 51 and connected thereto by means of a pivot pin 53. The pin 50 is rigid with the free end of the member 52 and the end portion of the bracket 51 received between the parts of the member 52 is shaped so as to permit movement of the member in one direction but to form a stop surface 54 preventing movement in the other direction. A coiled contractile spring 55 connecting the pin 50 with a stationary pin 56 on the beam arm tends to swing the member 52 and therefore the pin 50 to the limit position determined by the stop 54. In this position a roller 57a on the pin 50 (Fig. 5) is engaged by a rearwardly projecting portion 57 on the brake shoe.

45 The springs 55 for the respective pins are sufficiently strong to support the weight of the shoes holding the pins in position as determined by the stop 54. On the other hand, the springs permit yielding of the pins when the beam arms 14 are swung upwardly while the brake shoes remain stationary. This occurs in the operation of doffing a beam, while the beam is suspended by other means.

50 As shown in Fig. 3, the brake shoes 31 are pivotally supported at a point forwardly of the rod 33 constituting the pivotal axis of the beam arms 14. Accordingly, as the yarn mass being wound increases in diameter, the position of each 55 brake shoe with respect to the beam arm changes

constantly. In order to maintain the brake shoes uniformly spaced from the beam heads, the projecting members 57 of the brake shoes are appropriately shaped as shown in Fig. 3 so as to form rounded cam surfaces 57a for coaction with the pins 59 in various relative positions of the parts.

I claim as my invention:

1. A warper having, in combination, a frame, a driving drum, means supporting in operative association with the drum a warper beam having a member rigid therewith forming an annular braking surface, a brake shoe for coaction with said member, a slide pivotally supporting the brake shoe and mounted on said frame for movement toward the beam, said brake shoe tending to swing by gravity toward said member, and means holding the brake shoe out of engagement with said member during the normal operation of the warper.

2. A warper having, in combination, a driving drum, means supporting in operative association with the drum a warper beam having a member rigid therewith forming an annular braking surface, a brake shoe for coaction with said member, a slide pivotally supporting the brake shoe and mounted for movement toward the beam, said brake shoe tending to swing by gravity toward said member, and means holding the brake shoe out of engagement with said member during the normal operation of the warper comprising a stop movable in a direction away from the beam, and a spring acting on said stop, said brake shoe being engageable with said stop so as to be supported thereby through said spring.

3. A warper having, in combination, a driving drum, means supporting in operative association with the drum a warp beam having heads at opposite ends, said supporting means including a pair of pivotal arms, brake means for stopping rotation of the warp beam including a pair of pivotally supported brake shoes tending to swing toward said heads, and means normally supporting the brake shoes out of engagement with the beam heads during normal operation of the warper comprising stops carried by the beam arms for coaction with respective ones of the brake shoes.

4. A warper having, in combination, a driving drum, means supporting in operative association with the drum a warp beam having heads at opposite ends, said supporting means including a pair of pivotal arms, brake means for stopping rotation of the warp beam including a pair of pivotally supported brake shoes tending to swing toward said heads, and cam means for controlling the position of the brake shoes in relation to the respective beam heads in various positions of the beam arms.

5. A warper having, in combination, a driving drum, means supporting in operative association with the drum a warp beam having circular heads at opposite ends, said supporting means including a pair of pivotally supported arms, brake means for stopping the beam comprising a shoe for coaction with one of said heads, a slide pivotally supporting the brake shoe and mounted for movement toward and from the beam, the shoe being pivotally supported on an axis disposed between the beam head and the pivotal support for the arm, means for actuating the slide to cause the brake shoe to engage its beam head, and means normally supporting the brake shoe against rocking movement with respect to

the beam head comprising a stop member carried by the beam arm and a cam member on the brake shoe for coaction with said stop member.

6. A warper having, in combination, a driving drum, means supporting in operative association with the drum a warp beam having circular heads at opposite ends, said supporting means including a pair of pivotally supported arms, brake means for stopping the beam comprising a shoe for coaction with one of said heads, a slide pivotally supporting the brake shoe and mounted for movement toward and from the beam, the shoe being pivotally supported on an axis disposed between the beam head and the pivotal support for the arm, means for actuating the slide to cause the brake shoe to engage its beam head, and means normally supporting the brake shoe against rocking movement with respect to the beam head comprising a stop member carried by the beam arm and a cam member on the brake shoe for coaction with said stop member, said stop member being supported for movement in a direction away from the beam head and a spring action upon said stop member to hold it yieldably against movement under the weight of the brake shoe.

7. A warper having, in combination, a frame, a driving drum, means supporting in operative association with the drum a warp beam having opposite beam heads, and a brake mechanism for interrupting rotation of the beam comprising a slide mounted on said frame for movement toward and from the beam, a brake shoe pivotally mounted on the slide for coaction with one of said beam heads, spring means for actuating the slide, and means releasably holding the slide against movement by said springs including a control shaft operatively associated with the slide, spring means for rocking said control shaft and detent means for releasably holding said control shaft against movement.

8. A warper having, in combination, a driving drum mounted for rotation on a horizontal axis, means supporting in operative association with the drum a warp beam having a beam head rigid therewith and forming an annular braking surface, a brake shoe for coaction with said surface, the means for supporting the warp beam comprising a pair of arms mounted to swing on a horizontal axis disposed at one side of the beam in laterally spaced relation thereto, a slide mounted for movement toward and from the beam at one side thereof, said brake shoe being pivoted to the slide at a point between the beam and the axis of said supporting arms, the pivotal axis of the brake shoe being disposed so as to cause the brake shoe to swing by gravity toward said beam head, means normally operative to hold the slide and therefore the brake shoe in retracted relation with respect to the beam head but releasable to permit application of the brake shoe to the head, and means on one of said arms operative in the retracted position of the slide to hold the brake shoe against pivotal movement into engagement with the beam head.

9. A warping apparatus comprising in combination, a driving drum, means supporting in operative association with said drum and on an axis parallel thereto a warp beam having a brake member rigid therewith and providing an annular braking surface, a brake shoe, a support for said shoe mounted for movement toward and from said annular braking surface, spring means urging said support in a direction to carry the shoe against said surface, means releasably hold-

ing the support against movement by said spring means, said shoe being also supported for pivotal movement, and means automatically controlling the position of the shoe in relation to said braking surface so as to hold the shoe out of engagement with the surface in various positions of the warp beam relative to the driving drum.
